UNITED STATES PATENT OFFICE.

GEORGE S. WITHAM, SE., OF HUDSON FALLS, NEW YORK, ASSIGNOR TO THE UNION
BAG & PAPER COMPANY, A CORPORATION OF NEW JERSEY.

MACHINE FOR MAKING PAPER OR FIBER TUBES OR CORES.

1,074,680.

Specification of Letters Patent.

Patented Oct. 7, 1913.

Application filed August 22, 1911. Serial No. 645,408.

To all whom it may concern:—

Be it known that I, GEORGE S. WITHAM, Sr., a citizen of the United States, residing at Hudson Falls, county of Washington, State of New York, have invented certain new and useful Improvements in Machines for Making Paper or Fiber Tubes or Cores, of which the following is a clear, full, and exact description.

10 This invention relates to machines for making paper or fiber tubes or cores, such as made by paper makers for use in shipping large rolls of paper to newspaper printing establishments. The said tubes or cores are 15 substitutes for the well-known iron cores before used, and the object of the present invention is to improve upon the means for making paper tubes or cores, which are nothing more than heavy tubes made of 20 many wrappings or convolutions of glued paper which is wrapped about a mandrel or winder shaft. As substitutes for iron cores, these paper cores or tubes prevent the large rolls of paper wound about them from collapsing at the center, keep them circular and permit the paper to be run completely out right down to the core. As these paper cores or tubes are ordinarily made, the machine is stopped from time to time and the 25 core or tube calipered in order to determine its finished diameter, and the ordinary way of getting it off of its mandrel or winding shaft is to attach a block at the end and to use a block and fall and man power. Under 30 the present invention this is done away with, the objects gained being those of automatically stopping the machine when the tube or core reaches the desired diameter; the lifting of one end of the mandrel or winder 35 shaft from its journal; and thereafter the forcing or stripping of the tube from the mandrel or winder shaft on which it is wound, so that the tube or core will be almost absolutely cylindrical and will be 40 made in the best possible manner.

Other objects are to provide an efficient and practical machine for the purposes mentioned.

These being among the objects of the present invention, the same consists of certain features of construction and combinations of parts to be hereinafter described and then claimed with reference to the accompanying

drawings illustrating a suitable embodiment of the invention, and in which—

Figure 1 is a front elevation of the machine; Fig. 2 a plan; Fig. 3 a transverse section on the line 3—3 Fig. 1; Fig. 4 is an enlarged detail view of the means for gagging or determinating the thickness of the tube or core to be formed and a portion of the automatic machine stop; Fig. 5 is an enlarged detail view of the means for removing or stripping a tube or core from its mandrel or winder shaft; and Figs. 6 and 7 are, respectively, views of opposite ends of the mandrel or winder shaft preferably employed.

Referring to the drawings, the frame 1 is of suitable construction, the ends thereof being connected as by a stiffening rod 1^a. The paper roll from which the paper is supplied for the formation of the tubes or cores is mounted on a shaft 3 at the rear of the machine and mounted in box bearings 4, the upper half boxes or bearings 5 being hinged at one end and provided at the other end with tension screws or devices 6, for the purpose of giving the web of paper or material the proper tension as it is drawn forward in unwinding. The web passes over a guide roller 7 mounted on the frame and between a pair of glue rolls 9 and 10, the lower of which dips into a glue pan 8. The upper glue roll 10 is journaled in boxes 11 which are guided in standards 12, rising from the frame 1, and which boxes are pressed downwardly by means of pressure screws 13. A sufficient amount of glue is taken up by the lower roll to spread a thin film of glue evenly across the lower surface of the web. The pressure screws 13 are adjustable so that the top glue roll may be run at any desired tension to squeeze the web between the nips of the glue rolls, thereby adjusting the amount of glue required for the surface of the web. After leaving the glue rolls, the web passes under another guide roll 14 at the front part of the machine and from thence upwardly to a mandrel or winder shaft 15. The web of paper is attached to said shaft by wrapping it around until the next ply comes on top of the first, when the tension on this grips it hard enough so that the web is drawn forward as the shaft revolves. Said winder

105

shaft 15 is mounted to turn in bearings 16, 17, respectively at the left and right hand ends of the shaft. A counter shaft 18 is provided which is journaled at one end in the frame and in the other end in an auxiliary frame 18^a, and it carries a gear 19 which meshes with a gear 20 on the winder shaft 15. On the counter shaft is a belt pulley 21 and a clutch 22, the movable member of which clutch is operable by a lever 23. A cord or flexible connection 24 is attached at one end to the outer end of said lever and is guided over a guide pulley 25, from whence it passes down to and is attached to a foot lever 26. Clutch cut-out member 27 is pivoted at 28 to lever 23 and to it is attached a retracting spring 29, the purpose of which is to automatically retract the cut-out member and disengage the clutch members, for the purpose to be hereinafter stated. For the purpose of holding the clutch members in engagement, the clutch cut-out member 27 is held by a hold-back or detent 30 mounted on the frame about midway of the length of the winder shaft, said member 27 having a notch 31 to be engaged by or with said detent 30.

In conjunction with the clutch cut-out member and concomitant parts, means are provided for gaging or determining the thickness of the tube or core which is being formed about the winder shaft and for automatically releasing the clutch cut-out member when the predetermined thickness has been obtained. Such means preferably comprise a stop or trip member 32 which is pivoted at 33 to a bracket or frame portion 32^a carried by the frame 1. Mounted on the free end of the clutch cut-out member 27 as shown more clearly in detail in Fig. 4, is an adjustable set screw 34 which furnishes an abutment for the trip member 32 for the purpose of gaging or determining the thickness of the tube. A latch 35 is mounted on said bracket 32^a, which latch is operable for the purpose of engaging and holding the stop or trip member 32 up out of inoperative position while starting the cores or tubes on the winder-shaft.

The operation of the clutch cut-out member 27 and allied parts is as follows:—The predetermined thickness of the tube or core to be formed is secured by releasing the stop or trip member 32 from latch 35 so that it will rest upon the winder shaft 15. The abutment screw 34 is then adjusted in the end of the clutch cut-out member to such position that if raised by a predetermined thickness of tube or core, the clutch cut-out member would be released from detent 30. It will be seen that as convolution after convolution of the tube or core is formed on the winder shaft, the stop or trip member 32 is gradually raised, which tends to gradually release the member 27 from the detent

30. As soon as the predetermined thickness of tube or core has been obtained, the outwardly moving stop or trip member 32 and abutment screw 34 act to instantly disengage the member 27 from the detent 30, whereupon the member 27 is retracted by its spring thus disengaging the clutch members and stopping the rotation of the counter shaft 18. By these means various diameters of formed tubes or cores may be obtained, and the machine automatically stopped. When the machine has stopped, the web of paper is severed from the formed tube or core and the same is ready to be removed or stripped from its winder shaft. To set the described parts previous to the formation of another tube or core, the foot or manually operated device 26 is depressed whereupon the clutch members are again engaged and the clutch cut-out member 27 is engaged with the detent 30; the other parts are then adjusted in an obvious manner.

Previous to the removal of the formed tube or core from the winder shaft, it is proposed under the present invention to lift one end of said shaft. This is accomplished through the medium of a lifting lever 36 pivoted at 37 to the frame 1 and provided with a lifting roller 38 mounted on an upright support 39, carried by said lever. A hinged support or link 39^a is connected with the frame 1 at one end at 41, and at the other end with upright support 39 so as to hold the latter in proper position and to guide the lifting roller properly in its movements. For maintaining the lifting lever 36 in its adjusted position a rack 42 is provided, the teeth of which are engaged by a spring pawl 43 mounted on said lever. The said lifting roller 38 is located directly under one end, preferably the left hand end, of the winder shaft, and receives the same in its groove. It is obvious that as the lifting lever 36 is moved downwardly, the roller 38 is moved upwardly and carries with it the end of the winder shaft resting thereon so that the latter is brought to inclined position and is raised sufficiently above the bearing at its raised end in order that the tube or core may be stripped off. The raising and inclination of the winder-shaft is permitted by reason of the fact that the bearing 17 is open at the top so that the shaft may be moved on the contact edge of gear 20 as a fulcrum. Obviously other suitable means to permit such movement may be used.

The removal of the formed tube or core is accomplished by the following means: A worm shaft counter to the winder shaft 15 is mounted in suitable bearings of frame 1 and is provided at one end with a drive pulley 45 which is ordinarily constantly driven, and is not stopped when the other portions of the machine are automatically stopped as

described. Parallel with the worm shaft 44 is a guide shaft 46 on which is hung, so as to be laterally shiftable thereon, a traveler arm 47. The rear end of said arm is guided on shaft 46, while the other end of the arm extends forwardly in convenient position to the operator. Said arm is provided with a half nut 48, the threads of which are adapted to mesh with and engage the worm shaft 44. Rising from the arm 47 is a stripper 49 which preferably extends transversely across one side of the winder-shaft or roll and is adapted to engage with that end of the tube or core which is opposite to the direction in which the pushing movement is applied, as shown in detail in Fig. 5. It will be observed that the stripper 49 extends in the direction of the movement of inclination of the winder shaft, so that when said shaft is inclined said stripper will be in operative relation to the end of the tube or core which is engaged by said stripper. When the winder shaft and the formed tube or core have been raised as before described, the operator takes hold of the traveler arm 47 and brings the stripper 49 in engagement with the end of the tube or core and engages the half nut 48 with the worm 44. As the worm shaft 44 is constantly rotated, the said shaft acts imminently upon the engaged parts to effect the removal and stripping off of the tube or core from the winder shaft. The winder shaft is then lowered to its bearings and another tube or core can be formed. The preferable form of winder shaft can be ascertained from Figs. 4 and 5 and from Figs. 6 and 7 which are views of opposite ends of the shaft. The main body of the shaft 15 is flat at one side at 51 and the flat surface tapers slightly from end to end of the shaft. Along the flat surface 51 the said body section is undercut so as to provide a slide-way 52, which is tapered from one end of the shaft to the other. The shaft consequently is doubly tapered, with the result that at one end of the shaft as shown in Fig. 6, the shaft is the most cut away in the direction of its radius and transversely, while at the opposite end as shown in Fig. 7, it is the least cut away. There is also a shaft completing section 53 which is of such cross section from end to end that when fitted properly against the flat and cut-away portion of the body section 15, the shaft is completed and made a substantially true cylinder. Said section 53 is of the same length as the body section and is flattened correspondingly to the body section, the same having a co-extensive tapered portion which is undercut and corresponds in cross section with that of the slide-way in which it is received. When the said sections are pushed together end for end, the winder shaft is ready to form a tube or core. Before the latter can be removed, it will be necessary to impart a

blow or blows to the small end of the shaft completing section with the result that the latter may be driven out a suitable distance to thereby reduce the diameter of the shaft at the point of location of the shaft completing section. The tube or core may now be removed by the means before described.

What I claim as new and of my invention is:—

1. In a machine of the class described, the combination with a frame, a winder shaft mounted in bearings thereof and adapted to wind a web thereon, driving gears, one of which is mounted on said shaft, and means for applying an adhesive to said web before it is wound on said shaft, of means for inclining said shaft on its said gear as a fulcrum and moving one end away from its bearing.

2. In a machine of the class described, the combination with a frame, a winder shaft mounted in bearings thereof and adapted to wind a web thereon, driving gears, one of which is mounted on said shaft, and means for applying an adhesive to said web before it is wound on said shaft, of a manually operable device movably mounted on said frame, and means operated by said device for inclining said shaft on its said gear as a fulcrum and for lifting one end of said shaft away from its bearing.

3. In a machine of the class described, the combination with a frame, a winder shaft mounted in bearings thereof and adapted to wind a web thereon, and means for applying an adhesive to said web before it is wound on said shaft, of a grooved roller arranged under and in contact with one end of said shaft, and means for raising and lowering said roller to incline said shaft.

4. In a machine of the class described, the combination with a frame, and a winder shaft supported thereby, and adapted to form a tube or core thereon, of a worm parallel with said shaft, and having a continuous helical thread, means operable by said worm for engaging the formed tube or core and stripping it from said shaft, and means for moving said means laterally and bodily away from said worm to disengage it therefrom.

5. In a machine of the class described, the combination with a frame, and a winder shaft supported thereby, and adapted to form a tube or core thereon, of a worm parallel with said shaft, a guide shaft parallel with said worm, and a traveler pivoted and guided on said guide shaft, and provided with a segmental nut adapted to be moved laterally by said traveler to mesh with said worm and with a stripper for engaging the formed tube or core and stripping it from said winder-shaft.

6. In a machine of the class described, the combination with a frame, and a winder

70

80

90

95

100

105

110

115

120

125

130

shaft supported thereby, and adapted to form a tube or core thereon, of a worm parallel with said shaft, means for inclining said shaft and moving one end away from its bearing, and means operable by said worm and provided with a stripper which extends in the direction of the movement of inclination of the winder-shaft and transversely across one side of said shaft for engaging the formed tube or core and stripping it from the said end of said shaft when the shaft is inclined.

7. In a machine of the class described, the combination with a winder-shaft, and driving means for rotating said shaft to wind a web thereon and form a tube or core, of a clutch for controlling the operation of said winder-shaft from said driving means, automatic clutch throw-out means, stationary means for restraining the action of said throw-out means, said throw-out means having a part engageable with said stationary restraining means, and a trip member located adjacent said tube or core and adapted to be engaged by the latter to positively trip said clutch throw-out means and release the same from said stationary restraining means to stop the motion of said winder-shaft.

8. In a machine of the class described, the combination with a winder-shaft, and driving means for rotating said shaft to wind a web thereon and form a tube or core, of a clutch for controlling the operation of said winder-shaft from said driving means, clutch throw-out means, a stop or trip member engageable by the formed tube or core to operate said clutch throw-out means when the said tube or core has reached the desired thickness, said clutch throw-out means having an extended portion opposite said trip member and said last two elements, namely the extended portion and said trip member, having a movement in the same direction away from said winder-shaft, and a member carried by one of said last two elements and adjustable thereon in the said direction toward the other of said two elements, with which, said adjustable member is adapted to engage.

9. In a machine of the class described, the combination with a winder-shaft, and driving means for rotating said shaft to wind a web thereon and form a tube or core, of a clutch for controlling the operation of said winder shaft from said driving means, clutch throw-out means, a stop or trip member engageable by the formed tube or core to operate said clutch throw-out means when the said tube or core has reached the desired thickness, means for determining the thickness of the tube or core, and a latch to engage and hold said stop or trip-member out of the way while starting a tube or core on said winder shaft.

10. In a machine of the class described,

the combination with a winder-shaft, and driving means for rotating said shaft to wind a web thereon and form a tube or core, of a clutch for controlling the operation of said winder-shaft from said driving means, clutch throw-out means, an adjustable thickness-gaging device carried by said means, and a gravitating trip member resting on the tube or core which is in process of formation, and arranged underneath and adapted to engage said gaging device and operate said clutch throw-out means when the desired thickness of tube or core has been formed.

11. In a machine of the class described, the combination with a winder-shaft, and driving means for rotating said shaft to wind a web thereon and form a tube or core, of a clutch for controlling the operation of said winder-shaft from said driving means, a longitudinally movable clutch cut-out member, a hold-back, said cut-out member being engageable with said hold-back, means tending to impart longitudinal movement to said cut-out member, and a trip member to be engaged by said tube or core and to release said clutch cut-out member from said hold-back to stop the machine.

12. In a machine of the class described, the combination with a winder-shaft, and driving means for rotating said shaft to wind a web thereon and form a tube or core, of a clutch for controlling the operation of said winder-shaft from said driving means, a longitudinally movable clutch cut-out member, a hold-back, said cut-out member being engageable with said hold-back, means tending to impart longitudinal movement to said cut-out member, a trip member to be engaged by said tube or core and to release said clutch cut-out member from said hold-back to stop the machine, and means for again throwing on said clutch and engaging said cut-out member with said hold-back.

13. In a machine of the class described, the combination of means for forming a tube or core, a hold-back, means engageable with said hold-back and adapted when released to automatically stop the forming movement, a pivoted movable member adapted to rest on the tube or core being formed, and adjusting means adjacent to and co-operating with that portion of said member located between its pivot and that end of said member which is nearest the forming means, said member being adapted to disengage said hold-back and its said engaging means.

14. In a machine of the class described, the combination of supporting means, means for forming a tube or core, a hold-back located on said supporting means above said forming means, means engageable with said hold-back and adapted when released to automatically stop the forming movement, a member pivoted on said supporting means

and adapted to rest on the tube or core being formed, and adjusting means adjacent to and coöperating with that portion of said member located between its pivot and that 5 end of said pivoted member which is nearest the forming means, said members being adapted to disengage said hold-back and its said engaging means.

15. In a machine of the class described, 10 the combination with a winder-shaft, and driving means for rotating said shaft to wind a web thereon and form a tube or core, of a clutch for controlling the operation of said winder-shaft from said driving means, 15 a longitudinally movable clutch cut-out member, a hold-back, one of which latter parts, that is to say said member and hold-back, is engageable with and movable laterally away from the other, means tending 20 to impart longitudinal movement to said cut-out member, and a trip member to be engaged by said tube or core and to disengage

said clutch-cut-out member and hold-back to stop the machine.

16. In a machine of the class described, 25 the combination of means for forming a tube or core, and stop and start mechanism comprising a clutch device for controlling the operation of said forming means, a longitudinally movable clutch operating member, a hold-back, means tending to move said clutch operating member away from said hold-back, means for longitudinally shifting said clutch operating member into engagement with said hold-back, and means 30 35 for disengaging said clutch operating member and hold-back when the desired thickness of tube or core has been produced.

Signed at Hudson Falls, N. Y., this 1st day of August 1911.
